PORTABLE SURFACE GRINDING MACHINE

Edwin G. Moffett, Mobile, Ala.

Application May 12, 1937, Serial No. 142,264

3 Claims. (Cl. 51—241)

This invention relates to grinders for slide valve seats of steam driven engines, pumps and other similar devices and has for the primary object the provision of a portable and inexpensive device of this character which will rapidly and efficiently reface a slide valve seat of a steam chest or like device without the necessity of disturbing or taking the engine or pump apart and which will reduce man power for such work and 5 permit accurate work to be accomplished and is readily adjustable so that the device may be adapted to different types and sizes of chests and valve seats.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a grinder constructed in accordance with my invention.

Figure 2 is a top plan view partly in section 25 illustrating the device.

Figure 3 is a sectional view taken on the line 3—3 of Figure 1.

Figure 4 is a sectional view taken on the line 4—4 of Figure 3.

Figure 5 is a fragmentary sectional view illustrating a feed mechanism taken on the line 5—5 of Figure 1.

Figure 6 is a fragmentary sectional view illustrating a modified form of my invention.

Referring in detail to the drawings, the numeral 1 indicates a combined attaching and supporting frame, including side members 2 each having a right angularly extending base flange 3 equipped with slots 4 to receive stud bolts 5 for detachably securing the combined attaching and supporting frame to a steam chest or like device after the cover has been removed for the purpose of exposing the valve seat of the chest and which is indicated by the character 6. The 15 slots 4 permit the frame 1 to be adjusted to fit on different sizes of chests.

Each side member is composed of sections A and B hingedly connected, as shown at 7, whereby the section A may swing upwardly relative to the section B. The upper edge of the section B has a groove 8 to receive a rib 9 on the section A. The rib 9 and groove 8 act to maintain the sections A and B in alignment. The sections B rotatably support a shaft 10 to which is secured a hand lever 11 for rotating the shaft in either

direction. Eccentric connections are provided between the shaft 10 and the sections A for the purpose of raising and lowering the sections A relative to the sections B and each eccentric connection consists of a disc 12 secured to the shaft 10 and having an eccentrically located slot 13 to receive a pin 14 secured to the section A.

The side members of the sections A have formed therein slots 15, 16 and 17, the walls of which form tracks. Combined rollers and journals 18 engage with the tracks formed by the slots 17 and slidably and rotatably receive a shaft 19 on which is secured a bed 20 and mounted on the bed is an electric motor 21 provided with a handle 22 and power takeoff shaft 23. The 10 shaft 19 being slidable transversely of the frame 1 also longitudinally of said frame 1 permits the electric motor 21 to be adjusted or moved both longitudinally and transversely of the frame or the valve seat 6.

Carriages 23' are slidably mounted on the side members 2 of the frame 1 and each straddles its respective side member and have journaled thereon rollers 24 which travel upon the tracks defined by the slots 15. Adjustably mounted on the carriages 23' are journals 25 which rotatably and slidably support a shaft 26. The bed 20 has bearings 27 to receive the shaft 26, the shaft 26 being both slidable and rotatable in the bearings 27. A sleeve 28 is keyed on the shaft 26 and has a portion on which is removably mounted a grinding disc or tool 19 and also has formed thereon a gear 30 which meshes with a gear 31 secured to the power shaft of the electric motor. The journals 25 being adjustable on the carriages 23' provide means for adjusting the grinding tool 29 towards and from the work and whenever it is desired to elevate the grinding tool from the work the hand lever 11 is actuated to raise the sections A from the sections B of the side 30 members 2.

Braces 32 are secured to the journals 25 and are rotatably mounted on the combined rollers and journals 18.

A feed shaft 33 is secured to the motor bed 20 45 and extends through the slot 16 in one of the side members 2 and also extends through an opening in one of the braces 32. A feed nut 34 is journaled on the last-named brace and meshes with the feed shaft 33. A pivotally mounted 50 hand lever 35 is provided with a spring actuated double acting dog 36, either end of which may engage with a ratchet gear 37 forming a part of the feed nut whereby the feed nut may be rotated in either direction for the purpose of sliding the 55

motor 21 and grinding tool 29 transversely of the valve seat 6 in either direction.

From the foregoing description taken in connection with the accompanying drawings it will be seen that the grinding tool is advanced longitudinally of the work or valve seat 6 by the operator grasping the handle 22 of the motor and sliding the latter longitudinally of the frame 1. To adjust the grinding tool transversely of the work or valve seat the hand lever 35 is actuated. To raise and lower the grinding tool into operative and inoperative positions with respect to the work the hand lever 11 is actuated. To adjust the working position of the grinding tool with respect to the work the journals 25 are adjusted on the carriages 23'. The adjustment of the journals 25 regulates the depth of cut made by the grinding tool. Further, it will be noted that a device of this kind can be easily applied and removed from the work and when applied to said work will be held against accidental displacement and may be readily adapted to work of different kinds and also it is to be understood that this device may be employed for refacing any surface of any device.

Adjustable stops 30' are mounted on the side members 2 of the frame for limiting the longitudinal movement of the carriages which in turn limits the longitudinal adjustment of the grinding device.

Referring to my modified form of invention as shown in Figure 6 the shaft 26 is non-rotatable and non-slidable and the bed of the motor is slidable thereon, also the grinding tool, the latter besides being slidable is rotatable on the shaft 26. A sleeve 26' is journaled on the shaft 26 and is received in the bearings of the motor vehicle and forms a support for the grinding tool, the latter being detachably secured to the sleeve.

What is claimed is:

1. A portable grinder comprising a frame; adjustable means for securing the frame to work, a shaft rotatably and slidably mounted on the frame, a motor bed secured to said shaft, carriages carried by said frame and movable longitudinally thereof, journals adjustably secured to

said carriages, a second shaft journaled in said bearings and having the motor bed journaled thereon, a power means carried by said bed, a grinding device connected to said power means and supported by the second shaft, a feed mechanism carried by the frame and connected to the bed for adjusting the latter transversely of the frame, and a handle secured to the motor for sliding the motor and grinding mechanism longitudinally of the frame.

2. A portable grinding device comprising an adjustable frame including side members each composed of separable sections adjustable towards and from each other, means for adjusting said sections relative to each other, carriages slidable on said side members and longitudinally thereof, a grinding mechanism adjustably mounted on said carriages and adjustable transversely of the frame, power means connected to said grinding mechanism, a support for said power means, and means mounting said support on the frame for adjustment longitudinally and transversely of said frame and adapted to be adjusted longitudinally by manual power applied to said power means, and means manually actuated for adjusting said support transversely of the frame.

3. A portable grinding device comprising an adjustable frame including side members each composed of separable sections adjustable towards and from each other, means for adjusting said sections relative to each other, carriages slidable on said side members and longitudinally thereof, a grinding mechanism adjustably mounted on said carriages and adjustable transversely of the frame, power means connected to said grinding mechanism, a support for said power means, means mounting said support on the frame for adjustment longitudinally and transversely of said frame and adapted to be adjusted longitudinally by manual power applied to said power means, means manually actuated for adjusting said support transversely of the frame, and adjustable means carried by the frame for limiting the longitudinal adjustment of the grinding mechanism relative to the frame.

EDWIN G. MOFFETT.
